UNITED STATES PATENT OFFICE.

GEORGE MESSIG, OF BROOKLYN, NEW YORK.

ROLL-SELECTING DEVICE.

Application filed March 1, 1921. Serial No. 448,875.

This invention relates to musical instrument players and particularly to orchestrions, player-pianos, organs, and other musical instruments adapted to automatically play a number of rolls.

An object of the invention is to provide a device which is of simple and inexpensive construction and adapted for the playing of roll music.

10 A further object is to construct the mechanism so that it will be highly efficient and yet substantially silent in its operation so as not to distract attention from the music.

15 A further and more detailed object is to provide for the quick and accurate movement of parts in changing from one music roll to another.

20 A further object is to so design the device that all of the parts thereof will be disposed in readily accessible positions to the end that they may be reached for adjustment and repairs whenever required.

25 A further object is to provide means automatically operable to maintain any one of the several music rolls employed in correct alignment with the tracker bar and with the take up spool.

30 A further detailed object is to construct the mechanism so that a single brake device will serve to tension all of the music rolls as they move successively to playing position.

35 Other objects and aims of the invention, more or less specific than those referred to above, will be in part obvious and in part pointed out in the course of the following description of the elements, combinations, arrangements of parts and applications of principles, constituting the invention, and 40 the scope of protection contemplated will be indicated in the appended claims.

In the accompanying drawings which are to be taken as a part of this specification, and in which I have shown merely a preferred form of embodiment of the invention:—

45 Figure 1 is a front elevational view of a mechanism constructed in accordance with the invention.

50 Fig. 2 is a section on line 2—2 of Fig. 1, looking in the direction of the arrows.

Fig. 3 is a section on line 3—3 of Fig. 1 looking in a direction of the arrows.

Fig. 4 is a vertical section through the

roll carrier and take-up roll, on the line of 55 4—4 of Fig. 1.

Fig. 5 is a perspective view of a part of the mechanism.

Fig. 6 is an elevational view of parts shown in Fig. 5 but in a different position. 60

Fig. 7 is a perspective view of driving and control mechanism for the rewind engaging wheel and take-up spool.

Fig. 8 is a vertical sectional view on line 8—8 of Fig. 1, with parts broken away. 65

Fig. 9 is a fragmentary detail plan view of a weighted arm employed.

Fig. 10 is a fragmentary detail plan view of a further arm employed.

Fig. 11 is a fragmentary detail view of 70 the takeup spool and associated parts as they appear when it rests.

Fig. 12 is a fragmentary detail sectional view of a part of the rewinding mechanism. 75

Fig. 13 is a fragmentary detail view of one side of the driving clutch mechanism.

Fig. 14 is a fragmentary detail sectional view of the driving clutch mechanism.

Fig. 15 is a diagrammatic view illustrating means employed to maintain the music sheet properly aligned with the tracker bar. 80

Fig. 16 is a diagrammatic view illustrating a means for controlling the motor. 85

Fig. 17 is a diagrammatic view illustrating a means to prevent sounding of notes during the rewinding operation.

Fig. 17^a is a plan view, on an enlarged scale, of the pneumatic 39, valve V¹, pin 47, 90 rod 41 and lever 40.

Referring to the drawings for describing in detail the structure therein illustrated the reference character A indicates a base member by which the several parts of the 95 present mechanism is carried, said base being adapted for mounting in an automatic player of any appropriate type. To this base is connected a series of uprights B', B², B³, and B⁴. A roll carrier W is supported on the uprights B² and B³ by means of a carrying shaft 150' which bears on rollers 150 and 151, as shown in Figs. 1, 2 and 3.

The roll carrier W has means for supporting a plurality of music rolls and when rotated will carry these rolls successively into playing position. In the illustration 10 rolls

are shown mounted in a circle between the carrier heads x and x' .

Each music roll is provided with a terminal cross rod 87, and near the bearing of each roll is a spring pressed detent a for holding the rod 87 in a notch in the edge of the head.

The shaft of each roll has an offset driving member 44 beyond the outer side of the carrier head x , while beyond the head x' each shaft extends as at 71 to thereby provide an appropriate abutment to be engaged by the arm 70 for rotating the carrier as will be presently described.

A main drive shaft 28 carries a drive wheel 27 which is driven by motor M thru suitable connections as for instance the belt 27.

A friction wheel 30 is fixed to shaft 28 arranged to drive a friction disc 31, the wheel 30 being movable longitudinally of the shaft for adjusting the speed of rotation of the disc 31. The disc 31 is mounted on a shaft 32 which, by worm wheel gearing 33, is adapted to drive shaft 34, the shaft 34 being in turn adapted to be clutched with shaft 37' of the takeup spool, said shaft 37' being rotatably mounted in uprights B' and B .

The playing position of the roll is shown in Figs. 1 and 4; and when a roll reaches this position, its rod 87 is engaged by two arms 88 and 89 (one on each side of the roll carrier), and is moved downwardly into the slots 105 which are provided to receive them in the two flanges C and C' of the takeup spool S. The takeup spool has meanwhile started to revolve, and, continuing, the walls of the slots 105 grip the terminal rod and cause the winding of the music sheet on to the spool thus drawing the music sheet over the tracker bar in the usual manner.

There usually are 4 or 5 selections on each roll. After each selection the motor should stop and the mechanism should remain at rest until started again by suitable means, as by pressing of the electric button 19 (Fig. 16), which trips the knife switch 22, or by depositing a coin in a slot box or other suitable coin controlled device, which is no part of this invention, and not illustrated.

At the end of the last selection the roll rewinds. As the paper with its rod attached leaves the takeup spool S, the rod carries up the arms 88 and 89 to their normal or upper positions.

As the arms 88 and 89 are thus moved upwardly the shaft 110 (Fig. 5), which carries said arms, causes a bell crank 64, secured, to its left end to press backwardly against an extension 63'' of the hanger 63' so as to move the nose 63 of said hanger backwardly from beneath the pin 90. The pin 90 is connected with the bellows P and its release allows the bellows to swing downwardly into

distended position under tension of a spring 65.

As the bellows opens a link 66, also connected with the bellows, operates to rock the shaft 67 by means of a cross arm 68. The shaft 67 transmits the power of the spring 65, to the lever 69 Fig. 1 and Fig. 2 and arm 70. The arm 70 engages one of the extension shafts or lugs 71, of the roll carrier, and moves it one step, putting the next roll in playing position.

A sudden jerk in this movement is prevented by the bellows P supported by standard B^5 which operates as a brake and prevents the parts from rapid movement. For this purpose the bellows is provided with a valve 78 (see Fig. 16). The valve 78 rests upon a seat 78' in the exhaust tube 79 and has a small hole 80 self cleaned by a guide wire 80'.

To play the next roll the magnet 24 is energized for releasing the lever 92, when it is seen that the weight 95 on this lever (Fig. 6), acting thru shoulder 109'' of the link 109', will throw the bell crank 64 (Fig. 5) over dead center shown in dotted lines in Fig. 3 and cause the spring 91 to rock the shaft 110.

The shoulder 109'' formed by the upper end of the slot 109 of the link 109' bears down the arm of the bell crank 64 when moving down from its upper position thereby causing the bell crank to be thrown to its forward position over the dead centre by the spring 91.

When, however, the transfer arms 88 and 89 are drawn up by the rod 87 the spring 91 throws the bell crank over the dead centre to its rear position, thereby partially rotating the shaft 110 and carrying the upper ends of the said arms 88 and 89 rearward of the rod 87 and in position to engage the rod 87 of the next music roll when, upon the further operation of the instrument, the lever 92 is again moved by the weight 95. This will cause the arms 88 and 89 to engage the terminal rod on the end of the music sheet and carry said rod downwardly to the takeup spool. During the playing of the first few passages of the music, the suction being on, the bellows P will draw together, against the tension of spring 65, and will be held in its upper or normal position by pin 90 being caught on the nose 63 of the hanger 63'. By this means the spring 65 is held tensioned, i. e., with energy stored therein ready to be released when required for bringing a subsequent music roll into playing position as already described. Energy is first stored in the springs 65 and 91 which energy is expended by the operation of the instrument, after which by the further operation of the instrument energy is re-stored again in the said springs.

The roll carrier is free to rotate with the

shaft 150' and this shaft in turn is free to move longitudinally upon its supporting rollers 150 and 151 to effect proper tracking of the music sheets over the tracker bar and 5 take up spool as will be later described. An arm 139' carries a wheel 140 which is grooved and rides over the notches 138 of a star wheel D fixed to the shaft 150', its purpose being to hold the roll carrier in any 10 position to which it may be rotated, while yet not interfering with the free longitudinal movement of the roll carrier.

This arm has a weight 139 attached to its rear end. The front end of the arm has a 15 motion in two planes, that is, it is made with a universal joint to allow the arm to move up or down, and from side to side, to keep the wheel 140 and arm 139' on the star wheel 138 as the roll carrier is centering and 20 moving from right to left.

Fig. 12 is a detail view of the rewind clutch member, and the rewind-engaging wheel 43. This wheel has securely fastened to it a stud 42", and the wheel with the 25 stud, revolves freely on shaft 28, unless clutch member 42' is shifted over to engage 42", which clutch member being keywayed onto shaft 28 will then revolve the engaging wheel 43.

Fig. 13 shows flat spring 116 with extensions 116' bearing on side of disc of the clutch member 35.

Figure 14 shows the clutch disc 37 and drive member 35. The drive member 35 is 30 keywayed onto shaft 34 and will drive the takeup spool whenever the drive member is slid to engage pin 107 thereof within one of the holes 36 of the disc 37.

Associated with the bellows P is a box 125, which is connected to the exhaust tube 79 by the tube 127. This box contains a pouch 126. At the center of the pouch is linked a wire 128, and this wire connects to a pallet 129. The pallet is hinged at 129', and is in position inside the bellows P. When the exhaust suction in tube 79, draws the bellows together, the purpose of the pallet 129 is to shut off the exhaust through the tube 133 and prevent the stop pneumatic 85 from collapsing while music is playing. Air should only be drawn out of tube 133 to collapse pneumatic 85 after a roll has been 35 completely rewound. No exhaust being in 79, 127, 125 on the rewind allows the pallet 129 to drop and permit the bellows P, to create its own suction, as it opens; having thus moved the roll carrier one step, the pneumatic 85, then raises the switch 23.

The two flaps or valves 131 and 132, act 40 as means for shutting off either tube 133 or 134, depending upon which of the tubes, 133 or 134, is being acted on to draw the pneumatic 85 together. Connection 134 acts to lift a switch after each selection on the

roll, while tube 133 acts to lift the switch 45 after a roll has rewound.

The orifices in the tracker bar must always align with the perforations of each music sheet and to that end, in lieu of the music sheet shifting sidewise, the tracker bar itself 50 may be automatically caused to have a lateral movement in a similar manner as has the shaft 150' shown in Figures 1 and 15, thereby aligning the said two sets of orifices.

The brake for the take-up spool is shown 55 in Fig. 7. It comprises a flat spring 136 having a leather button at its upper end arranged to bear against the side of the clutch disc 37. An extension 137 of the spring 136 projects into the path of the lever 40 so that when said lever swings it will push said spring away from the side of the disc 37 for releasing brake pressure as the disc rotates in playing direction.

The brake for the music roll is shown by 60 43'. A flat strip of wood is pivoted in the back, a spring serves to bear it down on the flat surface of the engaging wheel 43, and thus act as a brake, to enable the paper of the music roll to keep tight over the tracker 65 bar, as it is being played. On rewinding, this brake is lifted from the surface of the wheel 43 by engagement of the lever 40, allowing easy driving of the rewind, while the 70 brake 136 for the take up spool is against the disc 37 on rewinding, to prevent the paper rewinding too loosely as it winds back on the music roll.

The operations and functions are as follows:—Referring to Fig. 16, pressing a button 19, or by means of a coin actuated mechanism, a circuit closes battery 20, with a magnet 21, and pulls over armature 22. This drops the knife switch 23 closing the heavier current connection to the motor M, and a 105 parallel circuit to the magnet 24 which is wound to the same resistance as the motor. The circuit of magnet 24 will however close at 26 only provided the large bellows P is 110 down.

The motor drives belt 27 and thereby rotates shaft 28 in a clockwise direction. The friction drive wheel 30 on this shaft drives the disc 31 which in turn drives the shaft 34 and the take-up spool S.

When the playing of a roll has been completed a suitably arranged perforation on the music sheet will expose a hole in the tracker bar T, and through this hole the 115 rewind pneumatic 39 (Fig. 7) will draw over 120 the rewind lever 40, by means of arm 41. The travel of air from the tracker bar to cause this pneumatic 39 to draw together is well known in this art and therefore needs no specific description here.

As the lever 40 (Figs. 1 and 7) is pivoted at its center, as at E, the lower half will slide the drive member 35, by means of stud 125

40', away from the clutch member 37 and thus free the takeup spool S. At the same time the upper half of the lever will slide the rewind clutch member 42 into engagement with a fixed extension 42" of the wheel 43, by means of a stud 40", and thus cause the roll to be rewound.

Suitable paddle like studs, as F, on wheel 43 engage with the extension arm 44 of spindle 45 of the music roll. These studs F operate as a means to connect the spindles 28 and 45, it being noted that whenever the roll carrier moves to dispose a roll in playing position the arm 44 of said roll will be brought into position for engagement by one of said studs.

A single brake member as 43' operating upon the periphery of the wheel 43 will be sufficient for controlling all of the music rolls as they are brought successively into playing position.

As it is necessary for the music to be silent during the rewinding operation I prefer to use a pair of valve chamber V^1 and V^2 respectively containing valves 49 and 57 and a small exhaust chamber or box 46. The rod 41, which is attached to the lower part of lever 40 for drawing over this lever also opens the valve V^1 , a small pin 47 on said rod being arranged to push against the arm 48 which carries the valve disc 49.

With my apparatus there is only one movement to change the roll after which the motor can be kept running without danger of injuring the music sheets.

The various parts of my instrument are designed to be placed to the front thereof as far as possible so that the operation of the same may be observed and also so as to be the more readily understood and repaired.

As soon as the hole in the valve block V^1 is opened, air rushes in and overbalances the partial vacuum in pouch 50, and vent 51, in box 46, causing the pouch 50 to raise and lift the valve seat 52, thus exposing a large enough hole at 53 to weaken the suction through the main action chest, which is connected through pipe 54. The air is exhausted out of this box 46 through the same exhausting means as used for the main action, and by the seat 52 raising, the inrush of air is enough to cause leakage in the main action, and no notes will sound.

The other valve V^2 is affected and the valve disc 57 lifted from its seat as soon as the music sheet leaves the take-up spool S (Fig. 11). At this time the valve V^1 closes, as the lever 40 disengages from the catch 56 (Fig. 7) and allows the roll carrier W to turn and put another roll R in position to be played.

The one valve V^1 is enough to flush the action, and the other valve V^2 is for the pur-

pose of keeping it flushed until the next roll 65 comes down, and the paper covers the tracker bar, one turn of the take-up spool S, allowing the valve V^2 to seat again (Fig. 4).

As the paper starts across the tracker bar T, and having made approximately one-half of a revolution on spool S, the valve V^2 will close and a vacuum be again established in the main action chest and box 46, the valve V^2 having been previously opened by the dog 58 (Figs. 11 and 17) as its wheel 59 75 dropped in recess 60 of the take-up spool S.

The arm 70, which as above described, operates to step the roll carrier around, is shown in Fig. 10, and its manner of operation is shown in Fig. 2. From these figures 80 it will be seen that a small roller 72 is mounted on an auxiliary link 73 which is pivoted as at 73' to the link 70. A suitable spring G operates to hold the link 70 pressed upwardly while the auxiliary link 73 hangs 85 downwardly with its roller 72 riding upon a track 74 so as to keep the lug 71 of the music roll between two adjacent parts 75 and 76, the former being carried by the link 70 and the latter being carried by the link 73, and not permit the roll carrier to oscillate by momentum.

As the roller 72 reaches the end of track 74 it drops off of said end so that the part 76 is removed from the path of travel of lug 93 71. In this position of the roller 72 the roll carrier may be revolved freely by hand if desired, as when inserting new music rolls.

For continuous playing I have provided a small arm 82 (Fig. 5) attached to the front 100 portion of the large bellows P said arm being mounted so that it may be swung manually into either a vertical or horizontal position. When it is swung into a horizontal position then the bellows coming down, and having changed the music roll, said arm will press against the lever 81 and push it backwardly the same as if the magnet 24 had attracted it. In this way the rolls will be changed and played continuously as long as 105 the motor is kept running.

For continuous playing, without a coin controlled apparatus the motor keeps running and wire or link 85' is disconnected and arm 82 is left in a horizontal position. 115

If it is desired to stop the motor after each selection, the music roll sheet is prepared with a single hole after each of the selections. These holes register with a corresponding hole in the tracker bar which is connected to a valve in the main chest and as each hole of the sheet comes in to register with the hole of the tracker bar this valve operates and makes an exhaust connection of tube 184, collapsing the pneumatic 85 and lifting the switch 23.

In order to stop the motor after a roll has been completely rewound the tube 133 re-

ceives the vacuum and the bellows P, opening, creates its own suction and draws air out of the pneumatic 85 collapsing it and operating the switch in the same manner.

5 The exhaust to the holes on the tracker bar is not operative on the rewind, therefore it remains for the bellows P to effect this operation.

In order that the mechanism may, if desired, 10 be used in connection with a coin controlled device, I have provided means including, for instance, the contacts 26 to keep the main motor circuit on for playing as many tunes as coins deposited.

15 When the first coin is deposited, the knife switch drops, closing the motor circuit and starting the music. If two or more coins are inserted, one after the other, a suitable ratchet wheel, not shown, is pushed around 20 one tooth for each coin deposited, and it is necessary for each tooth to be set back again, one tooth at a time until the knife switch lifts again to stop the motor. There is a lug on the first tooth which lifts the knife switch. After each selection, the single hole 25 in the music sheet, called the stop hole, is the only one in view, and admits air to the corresponding opening in the tracker bar, to a valve in the main action chest, and this 30 valve operates the knife switch pneumatic, but instead of the pneumatic being connected direct to the knife switch, it connects to and moves the ratchet wheel one tooth back each time this stop hole appears. It is obvious 35 then, that if the ratchet is tripped but once, as by the dropping of a single coin, it will only have to be pushed back once, and if more times it will not raise the switch to stop the motor, until the last tooth is in its 40 place, then the motor will stop.

After the last tune on the roll has been played, there comes a rewind hole, and if there are more tunes to be played, after this 45 roll rewinds, the large pneumatic P comes down, changes the roll, presses, and closes the contact 26 and circuit to the magnet 24, which in turn draws over the starting lever 81, and proceeds to play the first tune or as many more tunes as are required, until the 50 knife switch opens, stopping the motor.

In this case it is not continuous, only playing according to the number of coins deposited; so that it is therefore necessary then, that the continuous arm 82, be moved 55 back or in vertical position.

It is also necessary to stop the motor after the roll is rewound, if the last tune on this roll is the last to be played, in respect to the coins inserted.

60 I prefer then to stop the motor M, by using the large pneumatic P, as a suction means to draw the air out of the small pneumatic 85, collapsing it and lifting the knife switch 23. It is understood that as soon as 65 the roll has rewound and the rod 87 is de-

livered back to its place in the carrier, the large pneumatic P, drops and changes the roll as already described.

Suitable guides 87' may be provided to 70 form the two walls of a channel or passage-way located in the arc of the movement of the ends of the transfer arms 88 and 89 and leading to the take-up spool S thereby serving, when said arms are engaged with a music sheet rod 87, to guide the terminal rods 75 87 to and from spool S.

The transfer arms 88 and 89 are thrown over dead center in both directions by action of a suitable tension spring 91 which is connected with the crank 64.

The starting lever 81 has the shoulder 94 which receives the pin 93 of lever 92 and serves to hold said lever in its upper or normal position until the lever is drawn backwardly by magnet 24.

At the same time that the starting lever 81 is drawn backwardly to release lever 92, 80 for sending down the arms 88 and 89 delivering the music sheet on to the take-up spool S, the link 97 which is connected to the starting lever pushes the arm 98 backwardly and thus turns shaft 99 so that the arm 100 of said shaft is caused to move away from the disc 106 of clutch member 35. This allows said clutch member 35—which is 95 forced forwardly by the pressure of the spring 116 and extension 116' against the same upon the movement of the lever 40—to slide and come over until its pin 107 engages one of the holes 36 of clutch disc 37. 100 It will be seen that by these connections the take-up spool is made to start rotating shortly after the end of the music sheet starts downwardly toward the spool. The downward movement of the end of the music 105 sheet continues, and the rotation of the spool also continues, until, when the slots 105 of the spool have moved into proper position to meet the wire rod 87 then the terminal rod 87 of the music sheet meets the slots 110 of the spool and moves into said slots, the slots thereafter carrying the rod and music sheet around the spool as the spool continues to rotate.

The arm 100 just referred to serves to 115 hold the clutch member 35 and its pin 107 away from the holes 36 of disc 37 of the stationary take up spool S and also at the time when the dog 56 disengages the rewind lever 40 to separate the rewind clutch members 120 42' and 42''. Then the roll carrier W takes a step to the next roll. If these clutch members were kept in contact then the extension arm 44 of the music roll would probably engage one of the studs F and thereby interfere with the rotation of carrier W.

125 It is not necessary for the pin 107 to engage and rotate shaft 37', and take-up spool, until the music sheet comes down as above described. At this time the flat spring 116, 130

which has already been tensioned by the attached movement of lever 40, is ready to operate, by means of its extension 116' bearing on disc 106 to slide over the member 35 with pin 107 as soon as arm 100 has been removed.

It will be noted that the clutch 35 to drive the take up spool S does not connect with the disc 37 until the starting bar rocks the shaft 99 and releases the clutch by the extension 100 sliding away from the disc 106 forming part of this clutch.

By the sequence of operations of the levers 81, 92 and 109', bell crank 64 and arms 88 and 89 the wire rod 87 of the music sheet is forced downwardly with a continuous movement until it reaches the take up spool S. The additional parts consisting of the engaging means formed by the shaft 99 carrying the arm 100 and the lever 81; and the two parts of the dual rotary actuating device comprising the sidewise moving disc 106 when released by the arm 100, and the pin 107 to revolve until finding an entrance in one of the holes 36 of the disc 37; and also the take up spool S with slot 105 of cam C rotating until it meets the wire 87 of the music sheet are each successively operated while the end of the music sheet is moving continuously in a downward direction, after which the music roll and the take up spool rotate simultaneously while the music sheet is being wound on the take up spool and also, in a reversed direction, while the music sheet is subsequently rewound on the music roll.

The weight 95 on lever 92, being sufficient to throw the arms 88 and 89 over dead center, would be too much for the music sheet to raise on returning the arms 88 and 89 back to their upper position. The suction of bellows P, acting through pin 108, and lever 109, will lift the weight during the time while the music is playing and thus have the arms 88 and 89 free to be readily lifted by the music sheet at the completion of the winding of the music sheet on the take up spool.

On shaft 110, carrying the arms 88 and 89 is a cam 111. This cam is intended to operate the locking lever 112 of the roll carrier W. This cam is so arranged that while the arms 88 and 89 are down said cam functions to hold the lever 112 in locking position, that is with its upper end portion 113 in engagement with pin 114, and so that when the arms are up the cam functions to permit the lever to swing, under tensions of spring 112', for moving the part 113 out of engagement with pin 114.

In order to release the dog 56 (Fig. 7) and disengage pin 42' from the pin 42" to allow free movement of the engaging wheel 43, which is necessary before the roll carrier can make the move to place the next roll in position, I use a roller 118, horizontally

which is attached on the shaft 67 (best shown in Figs. 1 and 7) which rocks with this shaft and trips the dog 56 by wheel 118 pressing on the fulcrum 53' of the dog 56 thereby releasing the lever 40 and the rewind clutch member 42 the moment the roll changing bellows comes down.

As a cushion to further prevent arms 88 and 89 coming down with a bang, I prefer to use a pneumatic 119, connected with a link rod 120, to bear against the open pneumatic, which while being compressed acts as a cushion.

The pneumatic 119—which merely serves as a cushion or dash pot to resist undue rapid movement of the link rod 120 connected with the shaft 110—is not necessarily fixedly connected to any of the moving parts of the instrument but is mounted on the post B² and merely has a leather flap inside of it to allow the pneumatic to fill up with air, when it opens, and when the link rod 120, bears against this opened pneumatic, the two arms 88 and 89 shown on Figs. 2 and 5 are prevented from coming down too quickly as the spring 91 (Fig. 5) pulls down these arms. The pneumatic acts like a shock absorber.

As the proper functioning of the machine demands a proper registration between the holes in the music sheet and the ports in the tracker bar, my construction is so designed to permit any one of the music sheets to automatically align as it goes across the tracker bar and is wound on the take up spool, and at present I accomplish this means of alignment over the tracker bar T, while music is playing, by the magnets 122, 123 (Fig. 1) on each end of roll carrier shaft 150' shifting the complete roll carrier and the rolls, keeping it centralized between two extended levers 125 and 126, depending on which way the music sheet shifts; the lever it touches closes the circuit, correcting the alignment each time it tends to shift.

In case of any undue movement of the music sheet to one side or the other, or if either edge of the music sheet should become ragged, warped, distorted by swelling, or should buckle, the said edge would run unevenly and would overlap the flange C of the take up spool S while being wound thereon thereby injuring or destroying the music sheet, whereby it becomes necessary for the successful operation of the instrument for the music sheet and music roll to be shifted from one side toward the other to maintain a medial position under such circumstances in order for the said sheet to be properly and evenly wound upon the take up spool, having the distorted edge, if any, lying within the said flange.

It is therefore to be understood that any one of the rolls on the roll carrier will automatically register with their proper holes.

on the tracker bar and be properly wound on the take up roll. In the event of the music sheet shifting from one side to the other, its position is immediately corrected.

- 5 My apparatus is particularly adapted to be used in connection with any automatic music playing instrument, as it comprises a simple and quick means of changing the roll to be played by turning the roll carrier step 10 by step, and also transfer means for moving the free end of the music sheet to the take up spool, and simple and efficient means for rotating said spool during said transfer and also for rewinding the music sheet on the 15 music roll. It is apparent that its parts may be changed, and some of its purposes used independent of others, so I do not therefore wish to be limited to its particular construction.
- 20 In view of maintaining its principles, I desire to obtain Letters Patent in the United States, setting forth my invention in the following claims.

I claim:

- 25 1. In an instrument of the class described, a music roll carrying a music sheet having a rod at the end thereof, a laterally movable shaft therefor, means to maintain the music roll shaft in a medial position, a take-up 30 spool having flanges spaced apart the width of the music sheet to receive the latter, transfer arms to move the music sheet rod to the take-up spool, means to cause the music sheet rod to register with the transfer arms, and 35 means to rotate the take-up spool whereby when the music sheet is wound from the music roll to the take-up spool the edges thereof shall at all times lie within the said flanges.
- 40 2. In an instrument of the class described, a music roll carrying a music sheet having a rod at the end thereof, a laterally movable shaft therefor, means located on opposite sides of the instrument to maintain the music 45 roll shaft in a medial position, a take-up spool having flanges spaced apart the width of the music sheet to receive the latter, transfer arms to move the music sheet rod to the take-up spool, means to cause the music sheet 50 rod to register with the transfer arms, and means to rotate the take-up spool whereby when the music sheet is wound from the music roll to the take-up spool the edges thereof shall at all times lie within the said flanges.
- 55 3. In an instrument of the class described, a music roll carrying a perforated music sheet having a rod at the end thereof, a laterally movable shaft therefor, a tracker bar having a series of perforations, means to continuously register the music roll with 60 relation to the tracker bar so that the perforations of the music sheet will register with those of the tracker bar, a take-up spool 65 having flanges spaced apart the width of the

music sheet to receive the latter, transfer arms to move the music sheet rod to register with the transfer arms, and means to rotate the take-up spool.

4. In an instrument of the class described, 70 a roll carrier containing a plurality of music rolls each carrying a music sheet having a rod at the end thereof, a laterally movable shaft therefor, means located at each side of said shaft to maintain each music roll and 75 the carrier therefor in a medial position, a take-up spool having flanges spaced apart the width of a music sheet to receive the latter, transfer arms to move each music sheet rod successively to the take-up spool, 80 means to cause each music sheet rod to successively register with the transfer arms, and means to rotate the take-up spool whereby when each music sheet is successively wound from the music roll to the take-up 85 spool the edges thereof shall at all times lie within the said flanges.

5. In an instrument of the class described, a roll carrier containing a plurality of music rolls each carrying a perforated music sheet 90 having a rod at the end thereof, a laterally movable shaft therefor, a tracker bar having a series of perforations, means located at each side of said shaft to maintain each music roll and the carrier therefor in a medial position to register each music roll successively with the tracker bar so that the perforations of the music sheet will continuously register with those of the tracker bar, a take-up spool having flanges spaced apart 95 the width of a music sheet to receive the latter, transfer arms to move each music sheet rod successively to the take-up spool, means to cause each music sheet rod to successively register with the transfer arms, and means to rotate the take-up spool whereby when each music sheet is successively wound from the music roll to the take-up spool the edges 100 thereof shall at all times lie within the said flanges.

6. In an instrument of the class described, a tracker bar, a rotatable roll carrier supporting a plurality of rolls each roll carrying a music sheet, means for registering each roll successively with relation to the tracker 115 bar, a take up spool having flanges spaced apart the width of the music sheets to receive the latter, and means to maintain each registered music roll shaft in a medial position whereby when the music sheet is wound 120 on the take up spool the edges thereof shall at all times lie within the said flanges, and a dual rotary actuating means to operate the take up spool with a continuous movement.

7. In an instrument of the class described, a roll carrier, means to move said carrier comprising a member to store energy, a trip to release said member to permit it to move said carrier, and means to re-store energy 125

- again to said member actuated by the further operation of the instrument.
8. In an instrument of the class described, a roll carrier, means to move said carrier comprising a member to store energy, means to expend such energy by the operation of the instrument, and means, whereby by the further operation of the instrument energy is re-stored in the said member.
10. 9. In an instrument of the class described, a roll carrier, means to move said carrier comprising a member to store energy, a trip to release said member to permit it to move said carrier, means to re-store energy again to said member actuated by the further operation of the instrument, a music sheet carried by the roll carrier, a take up spool, means to carry the end of the music sheet continuously in a downward direction to the take up spool, the latter having means to engage the end of the music sheet to wind the same thereon, and a dual rotary actuating device to operate the take-up spool with a continuous movement.
15. 10. In an instrument of the class described, a roll carrier supporting a music sheet, means to move said carrier comprising a member to store energy, a trip to release said member to permit it to move said carrier, means to re-store energy again to said member actuated by the further operation of the instrument, a take up spool, means to draw the music sheet to the take up spool with a continuous movement, and a dual rotary actuating means to operate the take up spool with a continuous movement.
20. 11. In an instrument of the class described, a take up spool, a music roll carrying a music sheet, means for moving the end of the sheet to the take up spool comprising a member storing energy releasable for operation, and means to re-store energy again to the said member actuated by the further operation of the instrument.
25. 12. In an instrument of the class described, a take up spool, a music roll carrying a music sheet, means for moving the end of the sheet to the take up spool comprising a member storing energy releasable for operation, and means to re-store energy again to the said member actuated by the further operation of the instrument, and a dual rotary actuating device to operate the take up spool with a continuous movement.
30. 13. In an instrument of the class described, a take up spool, a music roll carrying a music sheet, means for moving the end of the music sheet to the take up spool comprising a normally locked resiliently controlled lever operative when released by the instrument, and means for again holding the same under resilient control actuated by the further operation of the instrument.
35. 14. In an instrument of the class described, a driving motor, means for starting the same, means for stopping the motor comprising a pneumatic release, and devices actuated by the motor and comprising a roll carrier supporting a music sheet, a take up spool, transfer arms to draw the music sheet to the take up spool, and a dual rotary actuating means to operate the take up spool.
40. 15. In an instrument of the class described, a driving motor, means for starting the same, means for stopping the motor comprising a pneumatic release, and devices actuated by the motor and comprising a roll carrier supporting a music sheet, a take up spool, means to draw the music sheet downwardly to the take up spool with a continuous movement, and a dual rotary actuating means to operate the take up spool with a continuous movement during the downward movement of the music sheet.
45. 16. In an instrument of the class described, a music sheet roll carrier, a take up spool, means to carry the end of the music sheet continuously in a downward direction to the take up spool, the latter having means to engage the end of the music sheet to wind the same thereon, and a dual rotary actuating device to operate the take up spool with a continuous movement.
50. 17. In an instrument of the class described, a rotatable and laterally movable roll carrier having a projection, a rewind engaging member having a series of projections one of said projections engaging a projection of the roll being played to form a brake for the rewind engaging member as the roll and carrier move from side to side, and means to release the brake from said engaging member.
55. 18. In an instrument of the class described, a rotatable music roll carrier having a projection, a rewind engaging member having a series of projections, said projections adapted to engage that of the carrier and adapted to keep the roll being played in connection with the said engaging member.
60. 19. In an instrument of the class described, mean for playing a number of rolls, a roll carrier therefor, a star wheel fixed thereto, an arm under tension having a universal joint and carrying a roll to ride over the points of the star wheel when the latter is rotated.
65. 20. In an instrument of the class described, means for playing a number of rolls, a roll carrier therefor, a star wheel fixed thereto, an arm under tension having a universal joint and carrying a roll to ride over the points of the star wheel when the latter is rotated, and rewinding means for the roll carrier comprising a single brake wheel having a series of projections and having an axis parallel to the axis of the roll being rewound, the said means being adapted to engage any one of the rolls with the one brake wheel alone.
70. 21. In an instrument of the class described,

means for playing a number of rolls, re-winding means therefor comprising a single brake wheel having a series of projections and having an axis parallel to that of the 5 roll being rewound, the said means being adapted to engage any one of the rolls with the one brake wheel alone.

22. In an instrument of the class described, a roll, a music sheet carried thereby, a take 10 up spool, mechanism comprising a series of interworking elements to move the music sheet, devices comprising another series of interworking elements to actuate the take up spool, a common means set in motion by the 15 commencement of the operation of the instrument to simultaneously start the movement of the said mechanism and also that of the said devices, means to continue the operation of the said mechanism and of the 20 said devices until the music sheet and the take up spool are operatively engaged, and means to keep the take up spool in continuous rotation until the music sheet is wound thereon.

25. 23. In an instrument of the class described, a roll, a music sheet carried thereby, a take up spool, mechanism to move the music sheet, devices to actuate the take up spool, a common means set in motion by the instrument 30 to simultaneously start the movement of the said mechanism and also that of the said devices, means to continue the operation of the said mechanism and of the said devices until the music sheet and the take up 35 spool are operatively engaged, and means to keep the take up spool in continuous rotation until the music sheet is wound thereon.

24. In an instrument of the class described, a roll, a music sheet carried thereby, a take 40 up spool, mechanism comprising a series of interworking elements to move the music sheet, devices comprising another series of interworking elements to actuate the take up spool, a common means set in motion by the 45 commencement of the operation of the instrument to simultaneously start the movement of the said mechanism and also that of the said devices, means to continue the operation of the said mechanism and of the 50 said devices until the music sheet and the take up spool are operatively engaged, and means to keep the take up spool in continuous rotation until the music sheet is wound thereon, and also means to simultaneously reverse the 55 movement of the music sheet and that of the take up spool until the music sheet is re-wound on its roll, and means to then stop the movement of the said parts or else to repeat the said operation at will.

25. In an instrument of the class described, a roll, a music sheet carried thereby 60 a take up spool, mechanism to move the music sheet, devices to actuate the take up spool, a common means set in motion by the instrument to simultaneously start the movement of the said mechanism and also that of the 65 said devices, means to continue the opera-

tion of the said mechanism and of the said devices until the music sheet and the take up spool are operatively engaged, and means to keep the take up spool in continuous rotation until the music sheet is wound thereon, and also means to simultaneously reverse the movement of the music sheet and that of the take up spool until the music sheet is re-wound on its roll.

26. In an instrument of the class described, a roll, a music sheet carried thereby, a take up spool, mechanism comprising a series of interworking elements to move the music sheet, devices comprising another series of interworking elements to actuate the 75 take up spool, a common means set in motion by the commencement of the operation of the instrument to simultaneously start the movement of the said mechanism and also that of the said devices, means to continue the 80 operation of the said mechanism and of the said devices until the music sheet and the take up spool are operatively engaged, and means to keep the take up spool in continuous rotation until the music sheet is wound 90 thereon, and also means to simultaneously reverse the movement of the music sheet and that of the take up spool until the music sheet is re-wound on its roll, and means to then stop the movement of the said parts or 95 else to repeat the said operation at will.

27. In an instrument of the class described, a roll, a music sheet carried thereby, a take up spool, mechanism to move the music sheet, devices to actuate the take up 100 spool, a common means set in motion by the instrument to simultaneously start the movement of the said mechanism and also that of the said devices, means to continue the operation of the said mechanism and of the said 105 devices until the music sheet and the take up spool are operatively engaged, and means to keep the take up spool in continuous rotation until the music sheet is wound thereon, and also means to simultaneously reverse the 110 movement of the music sheet and that of the take up spool until the music sheet is re-wound on its roll, and means to then stop the movement of the said parts or else to repeat the said operation at will. 115

28. In an instrument of the class described, a roll carrier containing a plurality of rolls each carrying a music sheet, a take up roll, mechanism comprising a series of interworking elements to move the music sheet, devices comprising another series of interworking elements to actuate the take up spool, a common means set in motion by the commencement of the operation of the instrument to simultaneously start the movement of the said mechanism and also that of the said devices, means to continue the 120 operation of the said mechanism and of the said devices until the music sheet and the take up spool are operatively engaged, and 125

65 130

means to keep the take up spool in continuous rotation until the music sheet is wound thereon, and also means to simultaneously reverse the movement of the music sheet and that of the take up spool until the music sheet is re-wound on its roll, and means to rotate the roll carrier a sufficient distance to bring another roll in position to enable its music sheet and the take up spool to be in turn operated by the said mechanism and by the said devices and also by the said subsequently acting parts.

29. In an instrument of the class described, a roll carrier containing a plurality of rolls each carrying a music sheet, a take up spool, mechanism to move the music sheet, devices to actuate the take up spool, a common means set in motion by the instrument to simultaneously start the movement of the said mechanism and also that of the said devices, means to continue the operation of the said mechanism and of the said devices until the music sheet and the take up roll are operatively engaged, and means to keep the take up spool in continuous rotation until the music sheet is wound thereon, and also means to simultaneously reverse the movement of the music sheet and that of the take up spool until the music sheet is re-wound on its roll, and means to rotate the roll carrier a sufficient distance to bring another roll in position to enable the music sheet and the take up spool to be in turn operated by the said mechanism and by the said devices and also by the subsequently acting parts.

30. In an instrument of the class described, a roll carrier, means to move said carrier step by step comprising a member to store energy, and a trip actuated by the operation of the instrument and adapted to release said member and permit it to move said carrier, a pneumatic vent cushioning the operative movement of said member, and means to re-store energy again to said member actuated by the further operation of the instrument.

31. In an instrument of the class described, a music roll carrying a music sheet, a take-up spool, means to move the music roll step by step means to carry the end of the music sheet to the take-up spool comprising a member to store energy, means to expend such energy by the operation of the instrument, and means to re-store energy again to the said member actuated by the further operation of the instrument.

32. In an instrument of the class described, a motor, a roll carrier carrying a music sheet, a take-up spool, a direct drive shaft operated by the motor to actuate the roll carrier step by step, means to store en-

ergy, a friction device to operate the take-up spool, means to move the roll carrier and actuate the friction drive by the release of said stored energy, and means to re-store energy again to said member actuated by the further operation of the instrument.

33. In an instrument of the class described, a music roll carrying a music sheet, a take-up spool, means to move the music roll step by step, means to carry the end of the music sheet to the take-up spool comprising a member to store energy, means to expend such energy by the operation of the instrument, and means, whereby, by the further operation of the instrument, energy is again restored in the said member, and also means to move the take-up spool comprising a pneumatic device.

34. In an instrument of the class described, a music roll carrying a music sheet, a take-up spool, means to hold the music roll, means to move the end of the music sheet to the take-up spool, a member to store energy comprising a resiliently controlled lever acting when released by the operation of the instrument to move the end of the music sheet, and means, whereby, by the further operation of the instrument, energy is again re-store in the said member.

35. In an instrument of the class described, a music roll carrier, means to move said carrier one step comprising a member to store energy, means to expend such energy by the operation of the instrument comprising a trip adapted to release said member, a vent to regulate the operative movement of said member, and means whereby, by the further operation of the instrument, energy is again re-store in the said member.

36. In an instrument of the class described, a music roll carrier, means to move said carrier one step comprising a member to store energy, means to expend such energy by the operation of the instrument comprising a trip adapted to release said member, means to regulate the operative movement of said member, and means whereby, by the further operation of the instrument, energy is again re-store in the said member.

37. In an instrument of the class described, a music roll carrier containing a plurality of music rolls each carrying a perforated music sheet, a tracker bar having a series of perforations, and automatically operated means to consecutively register each music roll and the tracker bar so that the perforations of each music sheet will register with those of the tracker bar.

GEORGE MESSIG,
